DESIGN FOR A FILM SLIDE PROJECTOR

Joseph Palma, Jr., Chicago, Ill., assignor to G-M Laboratories, Inc., Chicago, Ill., a corporation
of Illinois

Application February 27, 1946, Serial No. 126,951

Term of patent 14 years

(Cl. D61—1)

To all whom it may concern:

Be it known that I, Joseph Palma, Jr., a citizen of the United States, residing at Chicago, in the county of Cook and State of Illinois, have invented a new, original, and ornamental Design for a Film Slide Projector, of which the following is a specification, reference being had to the accompanying drawing, forming a part thereof.

In the drawing the figure is a front perspective view of a film slide projector showing my new design, the opposite side presenting substantially the same appearance as the side shown.

I claim:

The ornamental design for a film slide projec-tor, as shown and described.

JOSEPH PALMA, JR.
